DESIGN FOR A DRESS

Celia Kawaller, New York, N. Y.

Application June 20, 1938, Serial No. 77,934

Term of patent 3½ years

To all whom it may concern:

Be it known that I, Celia Kawaller, a citizen of the United States of America, residing in city of New York, county of New York, and State of New York, have invented a new, original, and ornamental Design for a Dress, of which the following is a specification, reference being had to the accompanying drawing, forming part thereof,

Fig. 1 is a front view of a dress showing my new design.

Fig. 2 is a rear view thereof.

The characteristic feature of my design resides in the combination on the dress disclosed of the specific panels of ribbon trimmed embroidery in association with the ribbon ornaments as shown.

I claim:

The ornamental design for a dress, substantially as shown and described.

CELIA KAWALLER.
